US0D1040653S

(12) **United States Design Patent** (10) **Patent No.:** **US D1,040,653 S**
(45) **Date of Patent:** **** Sep. 3, 2024**

(54) **CLOSURE FOR A CONTAINER**

(71) Applicant: **H.J. Heinz Company Brands LLC**,
Pittsburgh, PA (US)

(72) Inventors: **Balint Hiltser**, Lent (NL); **Guus Lueb**,
Bennekom (NL)

(73) Assignee: **H.J. Heinz Company Brands LLC**,
Pittsburgh, PA (US)

(**) Term: **15 Years**

(21) Appl. No.: **29/911,270**

(22) Filed: **Aug. 31, 2023**

Related U.S. Application Data

(60) Continuation of application No. 29/834,025, filed on

Flannery LLP

(57) **CLAIM**

The ornamental design for a closure for a container, as shown
and described.

DESCRIPTION

FIG. 1 is a top perspective view of a closure for a container
in accordance with our new design in a closed configuration;
FIG. 2 is a front elevation view thereof;
FIG. 3 is a rear elevation view thereof;
FIG. 4 is a left side elevation view thereof, the right side
elevation view being a mirror image thereof;
FIG. 5 is a top plan view thereof;
FIG. 6 is a bottom plan view thereof;
FIG. 7 is a top perspective view of the closure of FIGS. 1-6
in an open configuration;
FIG. 8 is a front elevation view thereof;
FIG. 9 is a rear elevation view thereof;
FIG. 10 is a right side elevation view thereof, the left side
elevation view being a mirror image thereof;
FIG. 11 is a top plan view thereof; and,
FIG. 12 is a bottom plan view thereof.
The broken lines depict portions of the closure that form no
part of the claimed design.

1 Claim, 10 Drawing Sheets
